UNITED STATES PATENT OFFICE.

PAUL HOERING, OF BERLIN, GERMANY, ASSIGNOR TO THE FIRM OF TORFEOKS GESELLSCHAFT MIT BESCHRÄNKTER HAFTPFLICHT, OF BERLIN, GERMANY.

METHOD FOR COKING HYDROUS BITUMINOUS COMBUSTIBLES.

No. 894,647.

Specification of Letters Patent.

Patented July 28, 1908.

Application filed December 22, 1903. Serial No. 186,178.

To all whom it may concern:

Be it known that I, PAUL HOERING, a subject of the King of Würtemberg, and resident of Berlin, in the Kingdom of Prussia, German Empire, have invented a certain new and useful Method for Coking Hydrous Bituminous Combustibles, of which the following is a full, clear, and exact description.

My invention relates to improvements in the manufacture of coke from aqueous, bituminous combustibles, such as peat, brown coal, river-mud, and the like.

In my invention I do not permit the escape of steam from the substances operated upon.

15 The steam is generated in great quantities during the drying of aqueous bituminous combustibles, which precedes the coking, and I utilize this steam by causing it to act upon the material to be coked, for which coking a coke-oven of any kind may be used.

The essential feature of my process consists in heating the aqueous bituminous combustible to the exclusion of air, and in conducting the steam generated thereby, which

25 in some cases contains small admixtures of distillation gases, into the coking-zone of an oven for the production of coke.

My process constitutes an improvement upon similar processes now in use. Besides 30 utilizing the steam generated during the coking of the said aqueous, bituminous combustibles and thus saving the heat-energy consumed in the generation of the same for effecting a chemical reaction, an increased 35 yield of ammonia, tar and gas is attained by this process.

My process can be carried out in different ways: 1. By conducting the steam generated in the drying of the aqueous, bituminous combustibles together with any admixtures of distillation-gases it may contain, generated during the drying, directly to the material which is being coked at a higher temperature and then expelling the water gas 45 formed by the decomposed steam from the coke-oven. 2. By first superheating the said steam and admixtures of gases it may contain, and thereupon conducting it to the material which is being coked at a higher 50 temperature.

The collection of the steam and the conveying of the same to the material from which the gas is being extracted may be effected in different ways. I prefer an oven, which is 55 illustrated in the annexed drawings and in

my pending application filed May 2, 1905, Serial No. 258,474. But it is evident that other suitable ovens may be used for carrying out my invention. For conducting the steam into the coking-zone I recommend 60 different means.

The steam may be either conducted by a suction-conduit leading into the coking-zone of the oven, through which is effected, by means of sucking-apparatus, such as ex- 65 hausters and the like, the sucking of the steam and the conduction of the same into the coking-zone of the oven, the passing of the same through this zone and the expelling of the water gas out of the coking-zone and 70 out of the oven. The steam may, however, also be conducted to the material which is being degasified in a manner that the coke-oven is closed at the top and has only an outlet in the coking-zone. The steam generated 75 is then driven by its own tension through the material in the oven, and passing through the coking-zone forms water gas which escapes from the oven.

My new process does not require that the 80 drying and the coking of the aqueous bituminous combustibles should take place in one and the same oven. The drying may be effected in a special oven and the steam generated may be conducted to another oven in 85 which the same or another material is coked. On the whole I prefer however to do the drying and the coking of the material in one and the same oven. In order to reduce, as far as possible, the resistance the steam meets with 90 on its way through the material, I prefer to provide special conduits, channels or chambers connecting the zone in which the drying of the combustible takes place with the coking-zone. 95

In carrying out my new process, the steam generated together with its admixtures, will in this case, stream from the drying-zone into the said conduits and be conducted through the same into the coking-zone. The conduits may lie in the inside or on the outside of the oven, moreover, heat may be conducted to the conduits from the outside for the purpose of foreheating or overheating the steam. 100

My above described process is not identical with processes already known, in which likewise gases are generated, which are conducted from colder parts of the oven into the warmer zones of the same. But with these 110

processes there is no question of the production of coke, but of the gasification of the combustible, and further of a superheating of tar-oils for the fixing of gases. With my 5 new process coke is to be produced and the tar-oils are, as far as possible, to be preserved at the same time.

In the furnace shown in the drawing, 10 wherein Figure 1 is a vertical section, and Fig. 2 a transverse section on line 1—1 of Fig. 1, the material is fed thereto through the shaft or aperture C when the closing plate a has been opened. Through the latter passes a 15 movable rod b connected with a valve c. By means of this valve the chambers d and e of the furnace can be placed in communication with each other when desired.

The preliminary drying of the material to be coked takes place in the chamber d from 20 which the material passes to the chamber e through the valve c which is opened at intervals. In the chamber e the extraction of gas and coking of the material takes place. The steam produced by the drying process in the 25 chamber d is conducted downwards through chambers or conduits f to the chamber e where it is decomposed into water-gas which circulates in the coking zone and passes out through the conduit g together with the gases 30 produced by the coking process. The removal of the gases from the chamber e is effected by means of an exhaust fan g or the like. The whole or part of the gases is admitted to the chamber h through the flue l, 35 or a part of the gases can be conveyed through the pipes r and s to other apparatus in which their heat is utilized, or condensation or other treatment of the gases takes place. When a portion of the gases are to be 40 conveyed to another apparatus the valve or the slide t, arranged in the pipe s, is opened and the valve or slide u, arranged in the pipe r, is closed. But the valve t being closed and the valve u being opened the gas exhausted 45 from the chamber e is conveyed through the pipe r to a pipe v through which it enters into the chamber h together with the heating gases generated in another plant. In this chamber h inclosed by the brick-work jacket 50 B, the gases are burned and effect the external heating of the retort A. The products of combustion finally escape by an exit w. The air necessary for the combustion of the 55 gases may enter through an air inlet x (preferably arranged near the pipe v.) The removal of the material from the chamber e

takes place through the curved conduit k, in which the inclined slide i is arranged.

Having thus described my invention, I claim as new and desire to secure by Letters 60 Patent:—

1. The process herein described of coking aqueous bituminous combustibles, consisting in heating such combustibles under the exclusion of atmospheric air, and then admitting the steam generated from the said combustibles with any small admixture of gases it may contain, into the coking-zone of an oven for the production of coke. 65

2. The process herein described of coking aqueous bituminous combustibles, consisting in heating such combustibles under the exclusion of atmospheric air, heating the steam generated from said combustibles with any small admixture of gases it may contain, and 70 then admitting the heated steam and gases into the coking-zone of an oven for the production of coke. 75

3. The process herein described of coking aqueous bituminous combustibles, consisting in heating such combustibles outside of the coking chamber and under the exclusion of atmospheric air, and then admitting the steam generated from said combustibles with any small admixture of gases into the coking-zone of the oven. 80

4. The process herein described of coking aqueous bituminous combustibles, consisting in heating such combustibles outside of the coking chamber and under the exclusion of 85 atmospheric air, subjecting the steam generated from the combustibles with any small admixture of gases to the action of heat, and then admitting the heated steam and gases into the coking-zone of the oven. 90

5. The process herein described of coking aqueous bituminous combustibles, consisting in heating such combustibles in a separate chamber within the coking oven and under the exclusion of atmospheric air, and then admitting the steam generated from the combustibles with any small admixture of gases it may contain into the coking-zone of the oven. 95

In witness whereof I have hereunto signed my name this thirteenth day of November 100 1903, in the presence of two subscribing witnesses.

PAUL HOERING.
